Primary Examiner — Andrew Kerr

(57) **CLAIM**

The ornamental design for a combined bowl with lid, as shown and described.

DESCRIPTION

1.1 is an exploded view of the combined bowl with lid, showing my new design.

1.2 is a perspective view thereof.

1.3 is a view of the left side thereof.

1.4 is a view of the top thereof.

1.5 is a view of the bottom thereof.

1.6 is a view of the bottom of lid thereof, shown separately to show aspects of the design that are not visible when combined.

1.7 is a view of the left side thereof.

1.8 is a view of the top of bowl thereof, shown separately to show aspects of the design that are not visible when combined.

1.9 is a view of the left side thereof.

The broken lines in the drawings depict portions of the combined bowl with lid that form no part of the claimed design.
